(57) **CLAIM**

The ornamental design for a tape cartridge for tape printing machine, as shown and described.

DESCRIPTION

FIG. 1 is a perspective view of a tape cartridge for tape printing machine according to a first embodiment;

FIG. 2 is another perspective view thereof;

FIG. 3 is a top view thereof;

FIG. 4 is a front view thereof;

FIG. 5 is a right-side view thereof;

FIG. 6 is a left-side view thereof;

FIG. 7 is a bottom view thereof;

FIG. 8 is a rear view thereof;

FIG. 9 is a cross-sectional view thereof taken along the line 9-9 of FIG. 3;

FIG. 10 is a perspective view of the tape cartridge for tape printing machine according to a second embodiment;

FIG. 11 is another perspective view thereof;

FIG. 12 is a top view thereof;

FIG. 13 is a front view thereof;

FIG. 14 is a right-side view thereof;

FIG. 15 is a left-side view thereof;

FIG. 16 is a bottom view thereof;

FIG. 17 is a rear view thereof; and,

FIG. 18 is a cross-sectional view thereof taken along the line 18-18 of FIG. 12.

The broken lines depict environmental subject matter only and form no part of the claimed design.
